PACKAGE OF EQUIPMENT FOR A
PADDLE BALL GAME

Robert E. Rodgers, Jr., 10284 Cresta,
Los Angeles, Calif. 90064

Filed Oct. 3, 1966, Ser. No. 4,141

Term of patent 14 years

(Cl. D58—2)

The back is substantially plain and unornamented.

I claim:

The ornamental design for a package of equipment for a paddle ball game, as shown and described.
